UNITED STATES PATENT OFFICE.

FRANK P. LAWLER, OF SAN FRANCISCO, CALIFORNIA, ASSIGNOR TO GENERAL ELECTRIC COMPANY, A CORPORATION OF NEW YORK.

HIGH-TENSION SWITCH.

Application filed July 9, 1924. Serial No. 725,049.

My invention relates to improvements in high tension switch mechanisms of the general type disclosed in my Letters Patent No. 1,464,368, dated August 7, 1923, reissued 5 May 13, 1924, No. 15,838.

An object of my invention is to provide an improved construction of switch, of the general type disclosed in my Letters Patent aforesaid, and adapted for use either as a by-passing or as a disconnecting switch, wherein there is but one movable contact member. Further objects are to provide a compact arrangement of by-passing and disconnecting switches, an improved arrangement for 10 avoiding difficulties from sleet, snow or the like and an improved arrangement whereby one or more of the switch line terminals may be grounded.

My invention will be better understood on 20 reference to the following description when considered in connection with the accompanying drawings, and its scope will be pointed out in the appended claims.

Referring to the drawing, Fig. 1 shows a 25 circuit control mechanism in which my invention has been embodied; Fig. 2 is an isometric projection showing the relation between the various parts of the mechanism illustrated by Fig. 1; Fig. 3 is a sectional view taken on the line *a--b* of Fig. 1; Figs. 4, 4^a, and 5 are fragmentary views illustrating certain details in a modified form of the invention; and Figs. 6 and 7 are like views of a further modification.

Fig. 1 shows line sections 1 and 2 arranged to be interconnected either through a by-pass switch comprising switch line terminals 3 and 4, a movable contact 5 and a yieldable connection 6, or through switch line terminals 7 and 8, movable contacts 9 and 10, yieldable connections 11 and 12, and an oil switch 13. The contacts 7, 8, 9 and 10 operate as a disconnect switch for the oil switch 13. The yieldable connections are 40 each shown as comprising a pair of rods or bars, hinged together at a point intermediate the ends of the connection.

I deem the pivoted bar or grasshopper connection preferable for the by-pass switch 50 but any suitable connection which will yield to permit relative movement of the fixed and movable switch elements may be used. Any yieldable connection used for the by-pass switch must be arranged so as to prevent a

reduction in the striking distance between 55 the live parts and the frame work of the switch. For example, an ordinary flexible conductor could not be used alone to connect the switch line terminal 4 to the movable contact 5, since, when the switch is in the open position, this conductor would sag so that an arc might strike across from the conductor to the frame work. Such a flexible conductor may, however, be used in connection with the grasshopper connection since 60 it may be carried by the pivoted elements of the grasshopper connection. Flexible conductors may be substituted for the yieldable connections 11 and 12.

The line sections 1 and 2 are supported 70 by dead end insulators 14 and 15 suitably secured at opposite ends of a trackway 16. Stationary insulating pillars 17 and 18 are provided to support the switch line terminals 3 and 4 at opposite ends of the trackway 16. The line terminal 3 is provided with a switch contact arranged to be engaged by the cooperating switch contact 5 which is connected to the other line terminal 4 by the grasshopper connection 6.

The movable contact 5 is mounted on an insulating pillar 19 which is supported by a carriage 20 arranged to move along the trackway 16 for the purpose of bringing the contact 5 into and out of engagement with the stationary contact 3. The contact 5 is shown in a position intermediate its open and closed positions which are indicated by dotted lines to facilitate an understanding of the relation existing between the various parts of the apparatus. Grounding switches 21 and 22 hinged at the points 23 and 24 respectively, are arranged to be rotated between the rails or guide members of the trackway 16 into engagement with the stationary contact 3 and movable contact 5 when the by-pass switch is in open position. In their open positions the grounding switches 21 and 22 lie beneath the trackway 16 in a position to permit movement of the carriage 20 along the trackway 16. The means for effecting movement of the carriage 20 is described hereinafter in connection with Fig. 2.

The switch line terminals 7 and 8 are 105 mounted on insulating pillars 25 and 26 supported at opposite ends of a trackway 27. The movable contact 9 is mounted on an in-

- sulator 28 which is supported by a carriage 29 arranged to move along the trackway 27. The movable contact 10 is likewise mounted on an insulator 30 which is supported by a carriage 31 arranged to move along the trackway 27. As will be readily understood upon explanation of Fig. 2, the carriages 29 and 31 are arranged to be moved in opposite directions in response to rotation of the shaft 32. In the positions of the carriages 29 and 31 illustrated by full lines in Fig. 1, the contacts 7 and 9 are in engagement, the contacts 8 and 10 are also in engagement, and the line sections 1 and 2 are connected to the terminals of the oil switch 13. When the movable contacts 9 and 10 are in the positions indicated by the dotted lines, the switch 13 is isolated from the line sections 1 and 2.
- As indicated by Fig. 2, movement of the carriage 20 is effected through a hand wheel 33, a shaft 34, cooperating gears 35 and 36, sprocket gears 37 and 38, sprocket chains 39 and 40, and idler pulleys 41 and 42, which are arranged to cooperate with wires, or the equivalent ropes 43 and 44. The sprocket chains 39 and 40 are attached to the car 20 at points 45 and 46 respectively, and to the wires 43 and 44 at points 47 and 48. The wires 43 and 44 are attached to the car 20 at points 49 and 50 respectively. Assuming the gear 35 to be in engagement with the gear 36, it will be apparent that the carriage 20 may be moved in either direction by manipulation of the hand wheel 33.
- Movement of the carriages 29 and 31 is also effected by means of the hand wheel 33 and shaft 34 upon which is mounted a gear 51 arranged to mesh with a gear 52. The gear 52 and the sprocket gears 53 and 54 are mounted in a shaft 32. Sprocket chains 55 and 56 are arranged to cooperate with sprocket gears 53 and 54. These chains are attached to the carriage 31 at points 57 and 58 respectively and to the carriage 29 at points 59 and 60. Wires, ropes or the equivalent, 61 and 62 are arranged to cooperate with idler pulleys 63 and 64 respectively. The wires are attached to the carriage 31 at points 65 and 66 and to the carriage 29 at their opposite ends. With this arrangement in mind, it will be readily understood that the cars 29 and 31 may be simultaneously moved in opposite directions by rotation of the hand wheel 33.
- At its lower end, the shaft 34 is provided with a coupling which permits it to move endwise either to bring the gear 35 into engagement with the gear 36, or to bring the gear 51 into engagement with the gear 52. This result is accomplished through a lever 67 pivoted at 68 and attached to a sleeve 69 at 70. The sleeve 69 is fixed at its upper end to the shaft 34 and at its lower end receives a short shaft upon which is mounted

the gear 71 and to which is fixed a pin 72, adapted to slide to and fro in a slot 73 in the sleeve 69 when the shaft 34 is raised and lowered. This arrangement acts as an interlock to prevent simultaneous operation of the carriage 20 and the carriages 29 and 31, and thus lessens the danger of mistakes in the operation of the air break by-pass and disconnect switches.

For the purpose of operating the ground- 75 ing switch 22, a shaft 74, hand wheel 75, shaft 76, gears 77, shaft 78 and gears 79 are provided. With this arrangement, the switch 22 is readily moved in response to rotation of the hand wheel 75. A like arrangement is provided for operating and grounding switch 21.

The operation of the switch mechanism shown in Figs. 1 and 2 may be stated briefly as follows: During normal operation the contacts 3 and 5 of the by-pass switch will be opened and the circuit between line conductors or sections 1 and 2 will be completed from line conductor 1, through the contacts 7 and 9 of the disconnecting switch, oil 90 switch 13 and thence through the contacts 8 and 10 of the disconnecting switch to line conductor 2. If it is desired to interrupt the circuit, this will be done by opening the oil switch 13, which may be any suitable switch 95 adapted to break high tension circuits under load. When it is desired to close the line circuit, this is also done by the oil switch 13. If it becomes desirable to work upon the oil switch for any reason and it is not 100 desired to interrupt the circuit through the line conductors 1 and 2, the contacts 3 and 5 of the by-pass switch may be closed, thus establishing a connection from line conductor 1 to line conductor 2 independently of 105 the circuit through the disconnecting and oil switches heretofore described. Since this circuit leads around the circuit through the oil switch, it constitutes a shunt or by-pass circuit. After the by-pass switch has been 110 closed the operator will open the oil switch 13 and then operate the disconnecting switch to disconnect the terminals of the oil switch from the line conductors by separating contacts 7 and 9, and 8 and 10. The oil switch 115 will then be dead and any desired work may be performed on it without danger. When it is desired to put the oil switch back into service the disconnecting switch contacts will be closed and then the oil switch closed, 120 after which the by-pass switch may be opened.

In the event that it becomes necessary to work upon the line conductors 1 or 2, or upon the mechanism of the by-pass switch 125 or the disconnecting switches, it is desirable to ground the line conductors 1 or 2, or both of them, and this may be done by the grounding switches 21 and 22. Before attempting to work on the line conductors, 130

precaution will be taken to disconnect them from any source of supply. The grounding switches may then be closed so that the workmen will be protected in the event that 5 the line conductors are inadvertently energized at some other point.

It will be observed that in my arrangement the by-pass and disconnecting switch mechanisms are arranged one above the 10 other and in the same plane. The trackways for the respective switch mechanisms may in this way be brought close together and the vertical space required is economized while at the same time no additional horizontal 15 space is required. While I have shown but one line circuit comprising the conductors 1 and 2, it will be understood that several of these switching mechanisms may be arranged side by side as described in my Letters Patent 1,464,368, heretofore referred to. For example, in a three-phase system three 20 of these switching mechanisms will be used, one for each line conductor. An increase in the number of switches involves no increase 25 in the number of operating shafts required, since the same shaft may operate the corresponding switch elements in each of the switch mechanisms.

Fig. 3 shows a cover 80 for protecting the 20 trackway 16 and the carriage 20 from accumulations of ice and snow which would interfere with their proper operation. It will be observed that this cover is slotted at its center to permit movement of the insulator 19 and to permit rotation of the grounding switches 21 and 22 which are mounted between the rails or guide members of the trackway 16. The cover 80 also affords some protection for the trackway 27 and 40 carriages 29 and 31. If desired, a separate cover may be placed immediately above the trackway 27.

In Figs. 1 and 3, the trackways 16 and 27 have been shown as comprising a pair of 45 channel members spaced apart to receive the wheels on the carriages. This arrangement while advantageous is not essential and may be replaced by any suitable means whereby the movable contacts of the by-pass and disconnect switches may be supported and moved to effect the operation described.

Figs. 4 and 5 show a different form of trackway and carriage. In this modification the trackway consists of an angle member 55 81. Arranged to cooperate with the member 81 is a carriage comprising a framework 82, a wheel 83 adapted to roll along the top of the member 81, and rollers 84 arranged to cooperate with the lower edges of 60 the member 81 to maintain the carriage in an upright position. Shims 85 may be provided to adjust the framework of the carriage to fit the member 81. A scraper diagrammatically indicated at 86, attached to the 65 framework 82, may be provided to remove

snow or ice which would interfere with the operation of the carriage. Similar scrapers may be provided, if necessary, for removing ice depending from the lower edges of the member 81. A sufficient clearance may be 70 provided between the sides of the framework 82 and the surfaces of member 81 so that it will be unnecessary to remove ordinary accumulations of sleet or snow from the member 81 except at the top, along which roller 83 moves, and in some cases at the bottom edges. The arrangement shown in Figs. 4 and 5 is well adapted for systems of moderately high tension but where the system is to operate in the neighborhood of 80 200,000 volts the provision of an angle member 81 of moderate size will not provide a sufficiently stable mounting for the movable insulator, which may be more than six feet 85 in height. It is obvious, however, that the angle member 81 may be replaced by a fabricated triangular structure comprising an angle member at the top of the triangle and rails at the bottom sides of the triangle. In this way, the support may be readily made 90 of a size to give sufficient stability for the carriage which carries the insulator.

While I have indicated the insulator carried at the top of the carriage in Figs. 4 and 5, it is apparent that the insulator may 95 be mounted at the bottom of the carriage instead of the top, as indicated in Fig. 4.

Figs. 6 and 7 show a modified combination of carriage, carriage cover and grounding switch. In this modification the hood 100 87 entirely covers the carriage and trackway. The movable insulator, when supported above the car, is mounted on a framework 88 which is underhung from the carriage 105 in a manner readily understood upon reference to the drawing. When the movable insulator is supported below the carriage, it may be attached to a member 89 supported above the channel members 90 and 91 at a 110 point near the middle of the carriage. Members 92 and 93 are attached to the under sides of the channel members 90 and 91 at opposite ends. The grounding switch 94 is pivoted at opposite sides of the trackway 115 and in its open position rests on the cover 87 so as to be within the framework 88 as the carriage is moved along the trackway.

It is apparent that the modification shown in Figs. 6 and 7 may be substituted in place of the corresponding arrangement shown in 120 Fig. 1. The modification shown in Figs. 4 and 5, if substituted in the by-pass switch arrangement of Fig. 1, would not permit operation of grounding switches arranged in the manner shown in Fig. 1. The arrangement is, however, adapted to be used without grounding switches or with grounding switches arranged for a less convenient and satisfactory operation. It is also adapted 125 where the insulators are underhung as indi- 130

cated in Fig. 4^a, for use in place of the disconnecting switch carriage arrangement shown in Fig. 1.

The modification shown in Figs. 4 and 5 is claimed specifically in my copending application, Serial No. 725,058, filed July 9, 1924, and the modification shown in Figs. 6 and 7 is specifically claimed in my copending application, Serial No. 725,048, filed July 9, 1924.

I have explained my invention by illustrating and describing certain specific embodiments thereof, but it will be readily understood by those skilled in the art that it may be embodied in other forms than those shown and described. I accordingly, do not wish to be restricted to the particular forms of construction disclosed herein by way of example for the purpose of setting forth my invention in accordance with the patent statutes. The terms of the appended claims are, therefore, not restricted to the precise structure disclosed, but are intended to cover all changes and modifications within the true spirit and scope of my invention.

What I claim as new and desire to secure by Letters Patent of the United States, is:—

1. In a mechanism for controlling a circuit through a power line, the combination of a trackway comprising a pair of guide members, a plurality of insulators, switch line terminals located at opposite ends of said trackway and supported by said insulators, a grounding switch rotatable between said members to ground one of said terminals, and means comprising a carriage movable along said trackway for interconnecting said terminals when said grounding switch is open.

2. In a mechanism for controlling a circuit through a power line, the combination of a trackway comprising a pair of guide members, a plurality of insulators, switch line terminals located at opposite ends of said trackway and supported by said insulators, means for interconnecting said terminals including a carriage movable along said trackway, an insulating pillar supported by said carriage, a movable contact mounted on said insulator and a conductor for interconnecting said movable contact with one of said terminals, and a grounding switch rotatable between said members to ground said movable contact when it is in open position.

3. In a mechanism for controlling a circuit through a power line, the combination of a trackway comprising a pair of guide members, a plurality of insulators, switch line terminals located at opposite ends of said trackway and supported by said insulators, a grounding switch pivoted between said members at one end of said trackway and arranged to ground one of said terminals, means for interconnecting said terminals including a carriage movable along said track-

way, an insulating pillar supported by said carriage, a movable contact mounted on said insulator and a conductor for interconnecting said movable contact with the other of said terminals, and a second grounding switch rotatable between said members to ground said movable contact when it is in open position.

4. In a mechanism for controlling circuits through a power line, the combination of a pair of trackways, a plurality of insulators, switch line terminals located at opposite ends of said trackways and supported by said insulators, means including carriages movable along said trackway for interconnecting the terminals located at their opposite ends, and means for operating said carriages said operating means being interlocked to prevent the simultaneous movement of carriages located on different trackways.

5. In a mechanism for controlling circuits through a power line, the combination of a pair of adjacent trackways located one above the other in the same plane, a plurality of insulators, switch line terminals located at opposite ends of said trackways and supported by said insulators, means including carriages movable along said trackways for interconnecting the terminals located at their opposite ends, and means for operating said carriages.

6. In a mechanism for controlling a circuit through an electric power line, the combination of a trackway, a plurality of insulators, switch line terminals located at opposite ends of said trackway and supported by said insulators, means comprising a carriage movable along said trackway for interconnecting said terminals, and a cover supported by said trackway for protecting said carriage and said trackway from the weather.

7. In a mechanism for controlling a circuit through an electric power line, the combination of a trackway comprising a pair of guide members, a plurality of insulators, switch line terminals located at opposite ends of said trackway and supported by said insulators, means comprising a carriage movable along said trackway for interconnecting said terminals, a grounding switch rotatable between said members for grounding one of said terminals, and a cover for protecting said carriage and said trackway from the weather, said cover being slotted to permit movement of said ground switch between its opened and closed positions.

8. In a mechanism for controlling a circuit through an electric power line, the combination of a trackway comprising a pair of guide members, a plurality of insulators, switch line terminals located at opposite ends of said trackway and supported by said insulators, a carriage movable along said trackway, an insulating pillar supported by

- said carriage, means including a movable contact mounted on said pillar for interconnecting said terminals, a grounding switch rotatable between said members for grounding one of said terminals and a cover for protecting said carriage and said trackway from the weather, said cover being slotted to receive said grounding switch and to permit movement of said pillar.
9. In a mechanism for controlling a circuit through an electric power line, the combination of a trackway comprising a pair of guide members, a plurality of insulators, switch line terminals located at opposite ends of said trackway and supported by said insulators, a carriage movable along said trackway, an insulating pillar supported by said carriage, means including a movable contact mounted on said pillar for interconnecting said terminals, grounding switches rotatable between said members for grounding one of said terminals and said movable contact, and a cover for protecting said carriage and said trackway from the weather, said cover being slotted to receive said grounding switches and to permit movement of said pillar.
10. In a mechanism for controlling a circuit through a power line, the combination of a pair of stationary insulators, line terminals supported by said insulators one of said terminals being provided with a switch contact, a movable insulator arranged between said stationary insulators, a cooperating contact mounted on said movable insulator mounted in alignment with said line terminals, means for moving said movable insulator bodily in a straight line between said fixed insulators to cause rectilinear engagement and disengagement of said cooperating contacts, and a yieldable connection permanently interconnecting said movable contact with the other of said terminals.
11. In a mechanism for controlling a circuit through a power line, the combination of a pair of stationary insulators, line terminals supported by said insulators one of said terminals being provided with a switch contact, a movable insulator arranged between said stationary insulators, a cooperating contact mounted on said movable insulator mounted in alignment with said line terminals, means for moving said movable insulator bodily in a straight line between said fixed insulators from a position adjacent one fixed insulator to a position adjacent the other fixed insulator to cause rectilinear engagement and disengagement of said cooperating contacts, and a yieldable connection permanently interconnecting said movable contact with the other of said terminals.

In witness whereof, I have hereunto set my hand this 27th day of June, 1924.

FRANK P. LAWLER.
